(57) **CLAIM**

The ornamental design for a bed, as shown and described.

DESCRIPTION

FIG. 1 is a front perspective view of a bed.

FIG. 2 is a front elevational view thereof.

FIG. 3 is a rear elevational view thereof.

FIG. 4 is a top plan view thereof.

FIG. 5 is a right side elevational view thereof; and, FIG. 6 is a left side elevational view thereof.

The broken lines represent portions of the bed and form no part of the claimed design.
